UNITED STATES PATENT OFFICE.

IRVING B. SMITH, OF PHILADELPHIA, PENNSYLVANIA, ASSIGNOR TO THE STOKES & SMITH COMPANY, OF PHILADELPHIA, PENNSYLVANIA, A CORPORATION OF NEW JERSEY

PIANISSIMO DEVICE FOR MUSICAL INSTRUMENTS.

No. 877,603.

Specification of Letters Patent.

Patented Jan. 28, 1908.

Application filed July 30, 1904. Serial No. 218,781.

To all whom it may concern:

Be it known that I, IRVING B. SMITH, a citizen of the United States, residing at Philadelphia, in the county of Philadelphia and State of Pennsylvania, have invented 5 new and useful Improvements in Pianissimo Devices for Musical Instruments, of which the following is a specification.

My present invention relates to tone-mufflers or pianissimo devices for pianos and other stringed musical instruments, and is especially adapted for use in connection with automatically operated pianos.

The main purpose of the invention is to 15 provide improvements in the class of mufflers that are constructed and arranged to be interposed at will between the hammers and the strings of the musical instrument in such manner that the musical tones may be muffled to a greater or less degree, accordingly, 20 as the performer may desire.

A further and important object of the invention, is to provide an improved muffler of the apron type, adapted to be interposed between 25 the hammers and strings of the piano, the construction and arrangement of the apron and its mounting being such that some of the musical tones may be muffled independently of and differently from others.

30 A still further purpose of the invention, is to provide a muffler of the apron type by which some of the musical tones may be muffled to a greater or less degree than others, whereby a note or group of notes at any 35 point along the key-board may be accented while others are subdued.

The invention has in view other important objects which will hereafter appear in the detailed description which is to follow this 40 statement.

Briefly and generally stated, the invention 45 comprises tone muffling means interposed between the hammers and the strings of the musical instrument, said means consisting of a plurality of members each comprising sections of material which differ from one another in their energy-transmitting or absorbing properties, and mechanism connected to the said members for moving them either 50 independently or unitedly to cause them, or either of them to assume various positions obliquely to the line of hammers, whereby some of the musical tones will be sounded louder than others.

55 In order to enable others to understand,

make and use my said invention, I will now proceed to describe the same in detail, reference being had for this purpose, to the accompanying drawings, in which—

Figure 1, is a vertical sectional view of a 60 portion of an upright piano, showing my improved muffler applied thereto; Fig. 2, is an enlarged detail sectional view of one form of muffler apron constructed according to my invention; Fig. 3, is a similar view of a 65 slightly modified form of muffler apron; Figs. 4 and 5, are similar views of other forms of muffler aprons within the spirit and scope of the invention; Fig. 6, is a perspective view of one form of mechanism for operating the 70 muffler; and Figs. 7, 8, 9, 10 and 11 are views showing some of the various positions the muffler may be caused to assume in order to produce different musical tone effects.

I will first describe one form of mechanism 75 for mounting and operating the muffler and will then describe the construction of the muffler itself, together with the manner of obtaining the various musical effects by shifting the position thereof relatively to the 80 hammers.

In the annexed drawing, Fig. 1, the reference numeral 1, designates the strings of a piano and 2, the actuating hammers, these elements being of the usual construction. 85 Secured to and projecting outward from the piano frame, are four brackets 3, 4, 5 and 6, said brackets being preferably located above the hammers 2, as more clearly shown in Fig. 6. Journalled in the outer ends of the 90 brackets 3 and 4, is a horizontal shaft 7, having secured to its opposite ends respectively, a rearwardly extending arm 8, and a forwardly extending arm 9. A sleeve 10, is fitted to turn freely on the inner end of the 95 shaft 7, said sleeve having its bearing in the bracket 4. This sleeve also carries a rearwardly extending arm 12, and a forwardly extending arm 13, the latter preferably overhanging the arm 9, as shown in Fig. 6. A 100 shaft 14, is journalled in the brackets 5 and 6, and this shaft has secured thereto at its opposite ends, a rearwardly extending arm 15, and a forwardly extending arm 16, as shown. The shafts 7 and 14, and the sleeve 10, are 105 in substantial horizontal alinement as will be seen, and the same is true of the rearwardly extending arms 8, 12 and 15.

To each of the forwardly extending arms 9, 13 and 16, is respectively secured a de- 110

pending rod 17, 18 and 19; the rod 17, being connected at its lower end to a lever 20, pivoted at 21; the rod 18, being connected at its lower end to a lever 22, pivoted at 23, and 5 the rod 19, being connected at its lower end to a lever 24, pivoted at 25. Each of the levers 20, 22 and 24, is provided at its outer free end with a finger key 26, said keys being marked respectively with the letters B, M 10 and T, indicating the bass, middle and treble strings of the piano, all for a purpose presently to be explained. The forward ends of the pivoted levers are normally held upward by suitable means, shown in the present instance as consisting of flat blade springs 27. It will be obvious that other forms of springs 15 may be employed for the purpose at hand, without departing from the spirit of the invention, the showing here made being only by way of example. The three operating levers may be located at any suitable point 20 on the piano, so as to be operated either by the hand or foot of the performer.

The foregoing description relates to one 25 form of mechanism for operating my improved muffler which I will now proceed to describe.

Secured to and depending from the rear 30 ends of the arms 8 and 12, is one member 28, of an apron muffler, and secured to and depending from the rear ends of the arms 12 and 15, is another member 29, of the apron muffler. These two members of the muffler 35 normally lie in horizontal alignment above the hammers 2, and either or both members may be lowered at the will of the performer, in a novel manner presently to be explained, so as to be interposed between the hammers and the strings.

40 In Fig. 2, I have illustrated one form of muffler constructed in accordance with this invention. As shown in this figure, the muffler members each consists of a single strip of felt or other similar material 30, 45 wedge shape in cross-section, or having one straight face 31, and an inclined face 32.

In Fig. 3, a somewhat similar form of muffler apron is shown, but instead of making the apron members from single pieces of material, they are each constructed of a plurality of strips 33, gradually decreasing in 50 length so as to provide on one side a series of stepped faces 34, as shown against which the hammers are adapted to strike. The several strips 33, are sewed together along their longitudinal edges as at 35.

55 In Fig. 4, I show another way of constructing the apron to produce the desired result. In this instance the members of the apron are made up of a strip 36, having longitudinally extending portions, or sections, of gradually varying density, said portions or sections being indicated by the letters a, b, c and d. I also show in Fig. 5, still another 60 way of forming the apron. In this case each

member of the apron 37, is woven in sections from strands of gradually increasing diameter, the section formed by the smaller strands being located at the lower edge of the apron, and the other sections following in the order 70 of the size of the strands, toward the upper edge of the apron. The different strand sections are indicated by the reference letters e, f, g and h.

In each form shown it will be seen that the 75 apron contains portions or longitudinal sections, of gradually varying resistance, formed either by the different thicknesses of the material of the apron, the difference in the density of the material or by the nature of the material employed. It will thus be seen if, some of the hammers are caused to strike their strings through the interposition of one section or portion of the apron, while others are caused to act upon their strings through the 80 interposition of another or different section or portion of the apron, that the resultant musical tones will vary; those struck through the portions or sections of greater density or thickness being softer than those struck 85 through the sections or portions of lesser density or thickness. By constructing the muffler apron in this manner, it will be apparent 90 that fine gradations in tone volume can be secured by shifting the position of the apron 95 relatively to the hammers. This is accomplished by the operating mechanism first described and the manner of securing some of the various gradations will now be described.

As before stated, the two members 28 and 100 29, of the muffler are secured to and depend from the arms 8, 12 and 15, and it will be apparent then if the key lettered B is depressed, that the arm 8 will be lowered and with it the outer end of the apron member 28, but the 105 opposite end of the section 28 will remain fixed. This depression of the key lettered B, will, therefore, move the apron member 28, on an inclined line relatively to the hammers as shown in Fig. 8, so that some of them 110 will strike along one portion of the apron while others will strike along other portions, and the resultant musical tones in the bass will vary gradually depending on the particular part of the muffler they strike. Should 115 the key lettered T, be depressed, then the arm 15, and outer end of the apron member 29, would be lowered on an inclined line, as shown in Fig. 9, the same as described with respect to the key B, and arm 8, and the 120 treble strings would then be correspondingly affected.

By simultaneously depressing the two outer key levers lettered B and T, the outer ends of the muffler members 28 and 29 will be 125 moved downward to cause said members to assume positions oblique to the line of hammers as indicated in Fig. 10, in which case diminuendo effects would be produced in both the treble and the bass from the middle 130

range outward, if the hammers were successively actuated accordingly. By depressing the middle key lettered M, the adjacent ends of the members 28 and 29, will be lowered to cause said members to assume the position oblique to the line of hammers as indicated in Fig. 11, and in this case crescendo effects would be produced in both the treble and the bass from the middle range outward, if the hammers were actuated successively in this order. By simultaneously operating all three key levers B, M and T, both members 28 and 29 of the muffler may be moved up or down as desired, the extent of movement being governed of course by the amount of depression given the keys. It is obvious that different key combinations will produce different and varied musical effects.

By the muffler means herein described it will be seen that a single note, a chord, or any given group of notes in any part of the keyboard range, may be accented or subdued as desired and that crescendo, diminuendo and other artistic musical effects produced.

I do not desire to limit myself to an apron made up of two members, as I may employ a greater or less number of members as desired, without departing from the spirit and scope of the invention as expressed in the appended claims. Likewise, I do not wish to be understood as limiting myself to the precise form of apron operating mechanism herein shown and described, for it is obvious that other operating means will readily suggest themselves.

What I claim is:—

1. A piano having tone muffling means interposed between the hammers and the strings, said means consisting of a plurality of members each comprising sections of material which differ from one another in their

energy-transmitting properties, and mechanism connected to the said members for moving them independently of each other to cause either section to assume various positions oblique to the line of hammers. 45

2. A piano having tone muffling means interposed between the hammers and the strings, said means consisting of a plurality of aprons each comprising sections of material which differ from one another in their energy-transmitting properties, and mechanism connected to said aprons for moving them independently of one another to cause either apron to assume a position oblique to the line of hammers. 50

3. A piano having tone muffling means interposed between the hammers and the strings, said means consisting of an apron comprising sections of material which differ from one another in their energy transmitting properties, and mechanism connected to said apron for flexing it intermediate its ends to cause different portions thereof to assume positions oblique to the line of hammers. 55

4. A piano having tone-muffling means interposed between the hammers and the strings, said means consisting of a plurality of members, each comprising sections of material which differ from one another in their energy transmitting properties, and mechanism connected to the said members to cause them to assume positions oblique to the line of hammers. 70

In testimony whereof I have hereunto set my hand in presence of two subscribing witnesses.

IRVING B. SMITH.
